UNITED STATES PATENT OFFICE.

RICHARD F. SCHULZKE, OF PORTLAND, OREGON, ASSIGNOR TO ZOSS LADDER WORKS,
OF PORTLAND, OREGON, A CORPORATION OF OREGON.

LADDER.

Application filed October 11, 1926. Serial No. 140,945.

The present invention relates primarily to step ladders, and more specifically to an improved construction for the fastening and supporting of the steps or treads upon the uprights of the step ladder.

The primary object of the invention resides in the provision of an improved type of bracket whereby the steps are rigidly anchored at their ends to the ladder uprights, in a manner whereby the steps are held against shifting laterally, and also against possible tilting.

A further object of the invention resides in the provision of a novelly constructed bracket for ladder steps, which may be economically stamped from sheet metal, and which bracket is of such construction as to permit of renewing of the steps should such become desirable.

Other objects and advantages of the invention will be apparent during the course of the following detailed description, taken in connection with the accompanying drawing forming a part of this specification and in which drawing:

Figure 1 is a fragmentary side elevation of the tread supporting uprights of a step ladder and showing the brackets applied thereto.

Figure 2 is a fragmentary front view of the ladder and showing the manner in which the treads are supported between the uprights.

Figure 3 is a detail fragmentary sectional view on line 3—3 of Figure 5 and showing the bracket in position for supporting of the tread.

Figure 4 is a perspective view of one of the brackets.

Figure 5 is a transverse section through one of the treads and taken on the line 5—5 of Figure 3.

Figure 6 is a plan view of the blank from which the brackets may be formed.

Referring to the drawing in detail, and wherein similar reference characters designate corresponding parts throughout the several views, the letter A may designate a ladder, embodying a pair of uprights or runpers B between which are mounted the steps or treads C as by means of the improved brackets D.

The uprights B and steps C, are preferably formed of wood, and with the steps being of rectangular shape in cross section for

providing flat upper and lower faces 8 and 9 respectively.

Referring now to the improved bracket D, and which may be stamped from sheet metal of a suitable gauge, the same is bent to form an end plate 10 having apertured right angularly extending ears 11 and 12 formed at its front and rear ends respectively. Bent inwardly at a right angle from the upper edge of the end plate 10, is a substantially triangular shaped tie plate 13 having an aperture 14 provided adjacent its inner end, and which plate is adapted to overlie in contacting relation, the upper face 8 of the tread C. Bent inwardly at a right angle from the lower edge of the end plate 10, and extending parallel with the tie plate 13, is a shelf or rest plate 15 of a length equal to the width of the tread C, and which rest engages in surface contact, the lower face 9 of the tread. Depending at an acute angle from the inner edge of the shelf 15, is a triangular shaped brace plate 16 having its lower end apertured as at 17 and offset in a plane parallel with the plane of the end plate 10. This offset portion of the brace plate 16 provides an attaching foot 18 adapted to engage in surface contact, the inner face of the upright B.

Struck outwardly from the end plate 10, and at a right angle from the plate, are V shaped tangs 19 which are adapted to be driven into the upright B at the inner face of the upright. These V shaped tangs 19 aid in preventing lateral sliding movement of the bracket across the inner face of the upright, and also aid in retaining the upper portion of the bracket in position when assembling the ladder.

A bolt or rivet 20 extends through the aperture 17 of the attaching foot 18, and the upright B for anchoring the lower end of the brace plate to the upright.

Struck from the shelf 15, and extending from the lower edge of the end plate 10, is a depending tongue 22 provided with a circular aperture 23 the upper edge of which lies in a like plane as that of the bottom face of the rest plate 15. This tongue 22, lies in surface contact against the inner face of the upright B.

Struck from the upper end of the brace plate 16, and extending in a like plane as that of the rest plate 15, is a horizontally disposed tongue 24 which forms a continu-

ation of the rest plate, and which tongue is provided with an aperture 25 adapted to align vertically with the aperture 14 of the tie plate 13. These apertures 14 and 25 are 5 adapted to receive a rivet 26 which extends vertically through the tread C, and which rivet serves for rigidly anchoring the bracket to the tread.

By observing Figure 5, it will be seen that 10 the aperture 23 is offset forwardly from the vertically aligning apertures 14 and 25, but that the aperture 23 is disposed rearwardly of the front edge of the opening 27 formed by the stamping out of the tongue 24.

15 This specific location of the aperture 23 permits of a tie rod 30 extending through the aperture 23 to extend longitudinally beneath the tread C in surface contact with the under face of the rest plates 15. This 20 tie rod 30 is adapted to extend through the uprights B and have its ends headed in any suitable manner at the outer faces of the uprights. Thus it will be seen that these 25 rods 30 prevent spreading of the uprights B and also form bearings for the opposite ends of the treads C.

The ears 11 and 12, which project over the front and rear edges respectively of the uprights, have fastening elements 32 in the 30 form of screws or nails, extending through the apertures thereof into the uprights, and which fastening elements serve for further fastening the brackets to the uprights. Thus it will be seen that if so desired, a tie 35 rod 30 need not necessarily be disposed beneath each tread, since the fastening elements 32 will serve for fastening the ends of the treads, together with the brackets, to the uprights B.

40 From the foregoing description it will be apparent that an improved and novelly constructed bracket has been provided for use

in the fastening of treads to the uprights of a ladder, in a manner whereby an extremely rigid and durable construction will be had, and which brackets may be economically stamped from sheet metal so formed as to effectively and efficiently tie the ends of the treads to the uprights against possible lateral shifting in either direction or allowing possible tilting of the treads when a considerable weight is applied to one edge of the tread. It will also be apparent that a novel construction has been provided whereby the tie rods for the treads also serve as a support for the treads at the uprights of the ladder.

Changes in detail may be made to the specific form of the invention herein shown and described, without departing from the spirit of the invention or the scope of the following claim.

I claim:

In a step ladder comprising uprights and treads extending between the uprights, means for securing the ends of the treads to the uprights, comprising bracket members each embodying an end plate having ears formed at the ends thereof for attachment to the front and rear edges of an upright, a rest plate extending inwardly from the lower edge of the end plate and having an apertured tongue, a brace plate depending at an acute angle from the inner end of the rest plate and having a foot portion at its lower end for attachment to the upright, a tie plate extending inwardly from the upper edge of the end plate and having an aperture for vertical alignment with the aperture in said tongue, and a fastening element passing through the tread and said aligning apertures for securing of the bracket to the tread.

RICHARD F. SCHULZKE.
